UNITED STATES PATENT OFFICE.

JOHN THOMAS BATT, OF PASADENA, CALIFORNIA.

GARMENT HANGER.

Application filed September 25, 1924. Serial No. 739,843.

The main objects of this invention are to provide an improved form of combined coat and trouser hanger; to provide a garment hanger having an improved form and arrangement of friction elements for securing a garment supported thereon against slipping; and to provide improved means for mounting the friction elements on the hanger.

10 An illustrative embodiment of this invention is shown in the accompanying drawing, wherein:

Fig. 1 is a side elevation, partly in section, of one form of the improved hanger, a fragmentary part of a garment being shown by dotted outline at one end of the hanger to illustrate the operation of the flexible friction elements.

Fig. 2 is a side elevation, on a reduced scale, showing the same hanger in tilted position, with a garment shown in dotted outline to illustrate the effect of the friction elements in preventing shifting of the garment.

25 Fig. 3 is an enlarged detail, partly in elevation and partly in section, illustrating how the friction elements may be applied to a wooden hanger.

Fig. 4 is an enlarged detail, in perspective, of one of the friction elements.

Fig. 5 is a transverse section of the supporting bar of the hanger taken on the line 5—5 of Fig. 1.

Fig. 6 is a transverse section of the bow of the hanger taken on the line 6—6 of Fig. 1.

Fig. 7 is a fragmentary plan of the supporting bar showing one of the key-hole slots in which one of the friction elements is adjustably mounted.

Fig. 8 is a detail in plan of a modified form of friction element.

In handling garments with the common form of hangers heretofore in use, a slight tilting of the hanger causes the garment to slide toward one side of the supporting bar or bow, necessitating readjustment of the garment to insure its being properly supported, and in the case of gowns and other garments of a flimsy texture a slight movement or tilting of the hanger frequently

causes the garment to slide off from the supporting bow.

In the construction shown, the hanger includes an improved form and arrangement 55 of friction elements which are mounted on the supporting members of the hanger in position to frictionally engage a garment supported thereon so as to prevent the garment from accidentally shifting or sliding 60 off of the hanger.

As illustrated in Figs. 1 and 2, the invention is applied to a metallic hanger comprising a bow 1, having mounted thereon a centrally located hook 2, by which the hanger 65 is suspended, and a cross bar 3. Mounted on the supporting bow 1 and cross bar 3, are friction elements 4 arranged adjacent each end of the hanger and positioned to frictionally engage the garments supported 70 thereon.

The supporting bow 1 and bar 3 are ar- 75 cuate in cross section, as shown in Figs. 5 and 6, so as not to present any sharp corners which would tend to crease the garments. The hook 2 is preferably swiveled in a bearing 5 in the bow 1. In order that the cross bar 3 may be of maximum length in proportion to the span of the bow, its end portions 6 are bent upwardly and then 80 inwardly at the ends of the bow 1 and are secured to the bow by rivets 7 or other suitable fastening means.

The friction elements are held in place by being inserted through apertures in the 85 bow and bar. The apertures 8 are prefer- 90 ably circular and smaller than the heads of the friction elements whereby the elements are securely retained. The apertures 9 are preferably in the form of key-hole slots dis- 95 posed longitudinally of the cross bar 3 so as to permit the friction elements supported therein to be adjusted to different positions along the hanger. The ends of the ap- 100 pertures 9 are enlarged as shown in Fig. 7 to facilitate the insertion and withdrawal of the friction elements. The best results are obtained when the friction elements on the cross bar 3 engage the garment close to the edges thereof, and for this reason these ele- 100 ments are arranged for lateral adjustment to accommodate garments of various widths.

The advantage of having the friction elements located close to the outer edges of the garment is that when the hanger is tilted as shown in Fig. 2, the garment, if of heavy material, will have a tendency to lift from the bar 3 and bear thereon only near its uppermost edge. If the friction elements are rather far from this edge, the garment would lift clear of them, and commencing to slide, would acquire a momentum which would overcome the resistance offered by the friction element when the garment engages it.

In the modified form shown in Fig. 3, the bow 10 is of wood and the friction element 4 is seated in a bore 12, having a reduced throat 13 at its upper end.

The friction element 4 is made of rubber or other suitable flexible material and is preferably serrated on its opposed faces to form gripping surfaces 14. A suitable shape for the element 4 is shown in Fig. 4 and comprises two similar heads or blocks connected by a contracted neck 15 which loosely fits the apertures 8 and 9 so as to permit the friction element to turn or swivel in its mounting, as hereinafter described. To insert the elastic elements 4 in the apertures of the hanger, the lower ends thereof are compressed and then after they have been inserted they resume the shape shown in Fig. 4 so as to be retained in their mountings. The medial portions of the key-hole slots 9 are slightly narrower than the thickness of the friction elements, so that the latter will be held in any position of adjustment by their own elastic expansion. The heads of the elements 4 project above and below the bow and cross bar so as to form tongues which are adapted to be flexed under the weight of the garment, or a movement thereof, and naturally assume the position best suited for resisting such movement.

If desired, friction elements 4.1 of wedge shape, as shown in Figure 8, may be used in place of the form shown in Figure 4. The reduced end of the wedge-shaped element may be readily inserted into the apertures in the bow 1 and cross bar 3 and the element then pulled through to a position where it would fit firmly.

In operation, the garments are supported on the bow and cross bar in the customary manner. The friction elements 4 on the bow assume positions transverse to the hanger and flex outwardly under the weight of the garment, as shown in Fig. 1. The flexible elements on the cross bar 3 are disposed longitudinally of the slots 9 so as to be flexed to either side of the cross bar when the hanger is held horizontally. If the garment tends to shift toward one side of the hanger, the weight thereof causes the friction element to turn in its bearing so as to locate the serrations on the gripping sur-

faces 14 in effective position for gripping the fabric. As shown in Figure 2, when the hanger is tilted, the garment on the cross bar 3 forces the uppermost friction element to turn at substantially right angles in its bearing, so that when the upper end of the element is flexed over against the cross bar the serrations will extend at substantially right angles to the plane of the hanger.

Although but certain embodiments of this invention have been herein shown and described, it will be understood that numerous details of the construction shown may be altered or omitted without departing from the spirit of this invention as defined by the following claims.

I claim:

1. A garment hanger comprising a supporting member having an opening formed therein, a flexible friction element having a part seated in said opening, one end of said element projecting to form a tongue having a gripping surface adapted to be flexed against said supporting member and to be turned relative thereto. 90

2. A garment hanger comprising a supporting member having an opening extending therethrough, and a flexible friction element loosely fitting in said opening so as to be turnable therein, one end of said element projecting beyond said supporting member to form a tongue adapted to be flexed against said supporting member. 95

3. A garment hanger comprising a supporting member having an opening extending therethrough, and a flexible friction element having a contracted neck portion loosely fitting in said opening so as to be turnable relative to said supporting member, one end of said element projecting beyond said supporting member to form a tongue adapted to be flexed against said supporting member. 100

4. A garment hanger comprising a supporting member having an opening extending therethrough, a rubber element having a centrally located contracted neck portion loosely mounted in said opening, the ends of said element being of greater width than said opening, one end of said element projecting beyond said supporting member to form a tongue adapted to be flexed against said supporting member and turned relative thereto, and gripping surfaces on said tongue. 110

5. A garment hanger comprising a supporting member having a longitudinally extending slot formed therein, and a flexible friction element having a part seated in said slot and being adjustable longitudinally of said support member, one end of said element projecting beyond said supporting member to form a tongue adapted to be flexed against said supporting member. 120

6. A garment hanger comprising a sup- 125

porting member having a longitudinally extending key-hole slot formed therein, a rubber element having a part seated in said slot so as to be adjustable longitudinally of said supporting member, said rubber element being normally of greater thickness than the width of said slot, one end of said element

projecting beyond said supporting member to form a tongue adapted to be flexed against said supporting member.

Signed at New York, N. Y., this 19th day of September, 1924.

JOHN THOMAS BATTIS.
